REEL HOLDER FOR BARBED WIRE

Louis A. Therrien, Pittsford, Vt.

Application August 22, 1950, Serial No. 180,870

3 Claims. (Cl. 242—90)

1

This invention relates to improvements in portable wire reel holders.

An object of this invention is to provide a portable wire reel holder which is particularly adapted to unreel barbed wire and the like with speed and facility.

Another object of this invention is to provide a portable wire reel holder which is particularly adapted to unreel barbed wire in a manner effectively minimizing the possibility of the wire tearing or cutting the body and clothing of the user.

A further object of this invention is to provide a portable wire reel holder which is provided with means for preventing idle rotation of the reel carrying the barbed wire on the portable holder.

A still further object of this invention is to provide a portable wire reel holder for unreeling barbed wire which is relatively simple in structure and cheap to manufacture.

The above and still further objects and advantages of the invention will become apparent upon consideration of the following detailed description of the invention, when taken in conjunction with the accompanying drawings, wherein:

Figure 1 is a front elevational view of a portable wire reel holder of the present invention;

Figure 2 is a sectional view taken along the line 2—2 of Figure 1;

Figure 3 is an enlarged sectional view taken along the line 3—3 of Figure 1;

Figure 4 is an enlarged fragmentary sectional view taken along the line 4—4 of Figure 1;

Figure 5 is a sectional view, with parts broken away, taken along the line 5—5 of Figure 1;

Figure 6 is an enlarged sectional view taken along the line 6—6 of Figure 1; and

Figure 7 is an enlarged fragmentary sectional view taken along the line 7—7 of Figure 1.

Referring now more particularly to the drawings, wherein like reference numerals have been used throughout the several views to designate like parts, the portable wire reel holder of the present invention, generally designated by the reference numeral 10, embodies a mobile frame 11 which includes an axle 12, wheels 13 and 14 rotatably journaled on each end of the axle 12 and adapted to traverse a ground surface, and an inverted, U-shaped frame 15 having the free ends of its legs 16 and 17 secured to the rearward side of the axle 12 inwardly of the wheels 13 and 14. As clearly shown in Figure 7, the wheel 14 is held on the axle 12 by means of a pair of trans-

2

versely extending cotter pins 18 and 19 disposed on opposite sides of the hub 20 of the wheel 14 and extending through the axle 12. The free end of the leg 17 of the U-shaped frame member 15 is secured to the axle by means of a bolt-and-nut assembly 21.

Spaced on the same level above the wheels 13 and 14 are blocks 22 and 23 which are secured to the rearward sides of the legs 16 and 17 of the U-shaped frame 15. Since the structure and securing of the blocks 22 and 23 is the same, it will suffice to describe only one in detail. Referring now to Figure 4, there is shown the block 23 having one face abutting against the leg 17 of the U-shaped frame 15 and secured thereto by means of a nut-and-bolt assembly 24. The exposed or outer face of the block 23 is provided with a shaft-receiving seat designated by the reference numeral 25. Abutting against the exposed face of the block 23 is an arm 26 which has one end pivotally supported on the bolt 24 for swinging movement into and out of bridging relation with respect to the shaft-receiving seat 25. The arm 26 can be fixedly secured in its position of bridging relation with respect to the shaft-engaging seat 25 by means of a bolt 27 which extends transversely through the leg 17 of the U-shaped frame member 15 and the block 23 and has its free threaded end projecting beyond the arm 26. Engaged about the bolt 27 is the nut 28 which is received within a bore provided in the exposed face of the block 23. Supported on the projecting end of the bolt 27 is a wing nut 29 which can be brought into and out of bearing engagement with the adjacent face of the arm 26. The arm 26 is provided with a slot 30, the bounding walls of which are engageable about the projecting end of the bolt 27 when the arm 26 is in its position of bridging relation with respect to the shaft-receiving seat 25. Accordingly, upon effecting the movement of the wing nut 29 along the threaded bolt 27 into bearing engagement with the arm 26, the latter can be fixedly secured in its position bridging the seat 25. The block 22 is similarly provided with a shaft-receiving seat, not shown, and a pivotally supported arm 30 is mounted in a manner similar to the arm 26 and provided with means 31 for securing the arm 30 in its position of bridging relation with respect to the adjacent one of the shaft-receiving seats.

Extending between the blocks 22 and 23 and having its opposed ends rotatably journaled in the shaft-receiving seats 25 is a shaft 33. As clearly shown in Figure 1, the shaft 33 is provided with enlarged collars 34 and 35 contiguous to each

of its ends preventing the transverse displacement of the shaft.

Carried by the shaft 33 intermediate the legs 16 and 17 of the U-shaped frame member 15 is a reel supporting mandrel, generally designated by the reference numeral 36 for supporting a reel carrying barbed wire to be unreeled, the reel being shown in phantom in Figure 1. The mandrel 36 comprises a pair of inwardly tapering sections 37 and 38 arranged in end-to-end, spaced relation with respect to each other and detachably secured about the shaft 33. The non-confronting or outward ends of the sections are provided with enlarged annular shoulders 39 and 40. The section 37 is secured to the shaft 33 by means of a transversely extending pin 41 which extends through the section and the adjacent portions of the shaft 33. Extending transversely through the shaft 33 contiguous to the confronting end of the section 38 is a pin 43 which has each of its projecting ends received within an L-shaped slot 44 provided in the confronting end of the section 38. Circumposed about the shaft 33 between the confronting ends of the sections 37 and 38 is a coil spring 45 which normally urges the section 38 away from the section 37 to thereby firmly seat the projecting ends of the pin 43 in the innermost ends of the L-shaped slots 44.

Spaced above the reel-supporting mandrel 36 is a pair of drag elements 47 and 48 fabricated of any suitable flexible material and adapted to engage the reel, shown in phantom, for retarding the latter to thereby prevent idle rotation of the reel with respect to the reel holder. As clearly shown in Figure 3, the drag element 47 is secured to the leg 16 of the U-shaped frame member 15 by means of a clamp 49 which has each of its free ends threaded and supporting nuts 50 and 51. Accordingly, the drag elements 47 and 48 can be detachably secured along the length of the legs 16 and 17 of the U-shaped frame member 15 for engagement with the reel.

Extending rearwardly from the U-shaped frame 15 above the drag elements 47 and 48 is a combined foot and handle 53. The foot 53 is U-shaped and, as shown in Figure 5, is secured to the legs 16 and 17 of the U-shaped frame member 15 by means of a securing plate 54 and bolts 55 and 56 straddling the free ends of the foot 53, the adjacent one of the legs of the U-shaped frame 15 and the adjacent end of the securing plate 54. The foot 53 may be utilized to support the U-shaped frame 50 at an angle relative to and upon the ground.

Intermediate the ends of the axle 12 and secured therebetween is an inverted U-shaped bracket 57 which has steel rollers 58 and 59 rotatably journaled on each of its legs. Rotatably journaled on the axle 12 intermediate the legs of the inverted U-shaped bracket 57 is another steel roller 60 which is supported for rotary movement about the axle 12. The rollers 58 and 59 and 60 cooperate together to form a guide means for paying out the barbed wire carried on the reel.

In actual use, the arms 22 and 23 are swung outwardly to the position illustrated in broken lines in Figure 1. The shaft 33 and the reel mandrel 36 are then removed from supported position within the reel-receiving seats 25, whereupon the movable mandrel section 38 is urged inwardly against the tension of the spring toward the stationary mandrel section 37. Upon effecting a slight rotation of the section 38, the projecting end of the pin 43 can be disengaged from the L-shaped slot 44 and the section 38 and the ad-

jacent spacing collar 35 removed from the shaft 33. A wire-bearing reel to be unreeled is then circumposed about the shaft 33 until one end of the reel abuts against the enlarged annular abutment 39 of the section 37. The section 38 is then manually grasped and once again engaged in its supported position on the shaft 33, the spacing of the annular abutment 40 being selected with respect to the annular abutment 39 to firmly hold the reel therebetween. The spacer collar 35 is then circumposed about the shaft 33 and the entire assembly once again supported in the position illustrated in Figure 1 intermediate the legs 16 and 17 of the U-shaped frame 15. The arms 26 and 30 are then manually grasped and brought into the position bridging the seats 25 provided in the blocks 22 and 23, whereupon the wing nuts 29 and 31 are engaged with the adjacent exposed faces of the arms 26 and 30. The drag elements 47 and 48 are then adjusted to engage the adjacent portions of the reel and the free end of the wire is inserted through the guide provided by the rollers 58, 59 and 60. The portable wire reel holder is now ready to unreel barbed wire with speed and facility.

Although only one embodiment of the wire reel holder of the present invention has been described, it is readily apparent that numerous modifications can be made without departing from the spirit of the invention as set forth in the appended claims.

What I claim is:

1. In a wire reel holder, a frame having laterally spaced straight legs, a rotary shaft extending between the frame legs, means removably journaling said shaft on the frame legs, a mandrel circumposed on said shaft between the frame legs, said mandrel comprising a fixed section and a rotatable and slidable removable section arranged in end to end relation, spring means compressed between the mandrel sections and urging the slidable section away from the fixed section, said removable section being removable from said shaft upon removing said shaft from the frame legs to enable removal and replacement of a wire reel on the mandrel sections, means on said shaft engageable with the end of said removable mandrel section remote from said fixed mandrel section positioning said removable section toward the fixed section so as to compress said spring means, and pin and slot means acting between said shaft and the opposite end of the removable mandrel section and releasably connecting the removable mandrel section for rotation with said shaft.

2. In a wire reel holder, a support, a shaft journalled on said support, a wire reel supporting mandrel circumposed on said shaft, said mandrel comprising a fixed section secured to said shaft to rotate with said shaft and a removable section rotatable and slidable on said shaft and removable from an end of the shaft, said sections having facing inner ends, the inner end of the removable section having an L-shaped slot including a portion opening through the inner end of the removable section, a laterally projecting pin on said shaft between the sections, said removable section being movable along the shaft toward said fixed section to engage said pin in said portion of the L-shaped slot and rotatable relative to the shaft to engage said pin in another portion of the L-shaped slot whereby endwise movement of the removable section is precluded, and spring means compressed between the facing inner ends of the sections serving to urge the removable section in a direction away from the

65
70
75

fixed section so as to produce retaining frictional engagement of said pin with said other portion of the L-shaped slot.

3. In a wire reel holder, a support, a shaft journalled on said support, a wire reel supporting mandrel circumsposed on said shaft, said mandrel comprising a fixed section secured to said shaft to rotate with said shaft and a removable section rotatable and slideable on said shaft and removable from an end of the shaft, said sections having facing inner ends, the inner end of the removable section having an L-shaped slot including a portion opening through the inner end of the removable section, a laterally projecting pin on shaft between the sections, said removable section being movable along the shaft toward said fixed section to engage said pin in said portion of the L-shaped slot and rotatable relative to the shaft to engage said pin in another portion of the L-shaped slot whereby endwise movement of the removable section is precluded, and spring means compressed between the facing inner ends of the sections serving to urge the removable section in a direction away from the fixed section so as to produce retaining frictional engagement of said pin with said other portion of the L-shaped slot, said mandrel sec-

tions having outer ends, and enlarged annular rest-end engaging shoulders on the outer ends of the sections.
